[57] CLAIM

The ornamental design for a terminal block, as shown and described.

DESCRIPTION

FIG. 1 is a perspective view of the terminal block showing my new design;

FIG. 2 is a front elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a rear elevational view thereof; and,

FIG. 8 is a perspective view of a series of terminal blocks disposed side-by-side.

The broken line showing throughout the drawings is included for the purpose of illustrating environmental structure only and forms no part of the claimed design.

1 Claim, 3 Drawing Sheets

FIG. 4

FIG. 2

FIG. 3
